UNITED STATES PATENT OFFICE.

WILLIAM H. C. HIGGINS, JR., OF LA PORTE, INDIANA, ASSIGNOR TO ADVANCE-RUMELY COMPANY, OF LA PORTE, INDIANA, A CORPORATION OF INDIANA.

CARBURETOR.

Application filed April 7, 1924. Serial No. 704,602.

This invention relates to a carburetor and particularly to a carburetor adapted for use with internal combustion engines mounted on an automotive vehicle, although it is not limited to this use. It has for one object to provide a carburetor in which positive means other than that of suction from the engine are provided for drawing fuel into the chamber of the carburetor. Other objects will appear from time to time throughout the specification and claims.

My invention is illustrated more or less diagrammatically in the accompanying drawings, wherein:

15 Figure 1 is a plan view of the carburetor with lid removed;

Figure 2 is a vertical cross section on line 2—2 of Figure 1;

20 Figure 3 is a vertical cross section on line 3—3 of Figure 2;

Figure 4 is a side elevation of the casing and associated parts.

Like parts are designated by like characters throughout.

25 A is a carburetor casing formed with a mixture passage, liquid chambers and other features which will be described below. A¹ is a fuel mixture passage provided preferably with a venturi A² and having located 30 within it a butterfly valve A³ adapted to control the flow through the passage A¹.

B is a fuel chamber communicating by means of the duct B¹ and the nozzle B² with the interior of the mixing chamber A¹. It 35 is adapted to be controlled by a needle valve B³ of any suitable type.

C is a fuel chamber similar to B, and it is connected similarly by a duct C¹ to a nozzle C² which is adapted to discharge fuel into 40 the interior of the mixing chamber A¹ and is adapted to be controlled by a needle valve C³.

45 Located within each of the fuel chambers B and C is a pump, the pumps being identical in construction and the description of one will suffice.

D is a cylinder fixed in the carburetor and positioned largely within the fuel chamber. Mounted within it for reciprocation is a hollow plunger D¹ which is ported at D² and terminates at its upper end in an enlarged laterally extending flange D³. About the plunger D¹ and bearing against the flange D³ is a washer D⁴. About the plunger and

50 bearing against the washer and tending to

hold the plunger in raised position is a helical spring D⁵.

Within the plunger D¹ is a bore E provided with a restricted portion E¹ intermediate its ends and having above said restricted portion a ball E².

55 The interior of the hollow plunger D¹ communicates with a supply line F which in turn, preferably through a suction check valve F¹ communicates with a supply line connection F² which is connected to any suitable fuel supply source.

60 G is a rocker shaft preferably squared at one end as at G¹. It has fixed upon it a lever G² which has pivoted to its lower end a connecting rod H, which has mounted at its outer end a follower H¹ adapted to bear upon a cam H² on the cam shaft H³ of the engine. About the connecting rod H is a helical spring H⁴ bearing against the carburetor 70 housing at one end and at the other against the follower H¹ tending to hold the follower in contact with the cam H². Through the cam, follower, and connecting rod assembly 75 the lever G² is moved and the shaft G is rocked by it. Fixed upon the shaft G are two levers M, M¹. Each of them preferably has a generally spherical contact face M².

80 The fuel chambers B and C as shown particularly in Figure 1 terminate short of the right side of the carburetor housing, as shown in Figures 1 and 3 particularly. To the right of the fuel chamber as shown in those views are overflow chambers J and K, 85 each of them communicating through a pipe J¹ and K¹ respectively with the main fuel source, so that fuel coming into the overflow chambers will be conducted back to the fuel source which may be any suitable tank or other storing device. On the carburetor 90 housing is a lid or cover L which is provided in its rear with an extending nose L¹ adapted to be contacted by a spring L². The spring acts to hold the cover in closed position and 95 also to hold it in the open position.

100 Although I have shown an operative device, still it will be obvious that many changes in size, shape and arrangement of parts may be made without departing materially from the spirit of my invention; and I wish, therefore, that my showing be taken as in a sense diagrammatic.

105 The use and operation of my invention are as follows:

110 When the carburetor is in operation it is,

of course, associated with an internal combustion engine and it is connected with a source of fuel supply. Fuel is initially introduced into the fuel chambers of the carburetor and the engine is started. When the carburetor is put into operation the suction of the air as it passes through the carburetor into the engine is sufficient to draw the fuel from the fuel chambers of the carburetor into the mixing chamber there to be mixed and carried on into the engine in the form of a combustible mixture. As the engine operates the pumps are operated through the connecting rod and lever assembly. The hollow pump cylinder of each pump is pressed downward, and as it does so pressure is created within that portion of the supply line between the ball valve in the hollow pump cylinder and the suction check valve, in the form here shown located just outside of the carburetor proper. This pressure is sufficient to unseat the ball and cause some discharge of the fuel in the fuel chamber. On the return stroke the hollow pump plunger is raised by the spring which surrounds it, suction is created, the ball is seated, and an additional amount of fuel is drawn past the suction check valve into the supply line between it and the ball valve. This operation is repeated when the pump plunger is forced down again and further discharge of fuel into the fuel chamber takes place. Thus the successive reciprocations of each of the pump plungers draw successive charges of fuel from the supply, past the suction check valve into the fuel chamber from which it may be drawn by means of the suction of the engine into the mixing chamber of the carburetor and so into the engine.

With each stroke of the pump a quantity of fuel greater than that which is necessary is drawn into the fuel chamber and some overflow takes place. This overflow takes place from the fuel chamber proper into the overflow chamber in the carburetor casing, and this overflow of fuel flows thence back along the return line to the main tank or other supply source.

By this means a compact assembly is provided both for feeding fuel to the carburetor and for carburetting the fuel for combustion. Since all the working parts of the pump, and particularly the plunger are protected from dust, the wear on the parts is considerably reduced. Since the pump parts work constantly in fuel, it is unnecessary to provide packing glands as the joint between the pump plunger and pump cylinder is at all times submerged. Thus a liquid seal is provided which is sufficient to prevent undue leakage, even after considerable wear of the parts has then place.

In some forms of the carburetor two different fuels may be used, in others a fuel and water may be used. And in case water is used, the delivery check valve is located

practically on a level with the delivery ports. Thus only a very small quantity of water can be entrapped above this delivery check or ball valve, and if freezing takes place no harm will be done. Thus special drainage means need not be provided above the delivery check valve, and in cold weather when the engine is to be left standing, it is necessary only to drain the chambers B and C and the under side of the pump between them and the suction check valve.

The flattened portion at the end of the rocker shaft is provided so that a wrench or other tool may be used to rock this shaft to operate the pumps by hand and thus to prime them.

The spring H⁴ is stronger than the spring D⁵ and thus if the pumps should freeze or stick for any other reason, no mechanical harm would be done as positive action of the cam and the connecting rod would simply impart motion to the parts up to and including the levers M, M¹, but the plunger D¹ would only be under the influence of the spring D⁵ which would not be sufficient to do any harm.

Looking at the device as shown particularly in Figure 3, if the plunger were stuck and the eccentric H² were pushing the follower H¹ and other connecting parts of the pump, this action would simply result in separating or raising the lever M¹ on the pump plunger. The plunger itself in that case would only be under the force of the spring D⁵ so as to raise it. If the cam shaft were on the return stroke the eccentric H² would merely run away, and the follower H¹ and the pump plunger would then be only under the force of the spring H⁴. The spring H⁴ thus tends to force the follower H¹ out and through it the connecting rod H and so to move the lever G and the lever M¹, and the spring H⁴ is not strong enough to move the parts to break them in case they are stuck either due to the freezing of the material about them or to sticking from any other cause.

I claim:

1. In a carburetor a plurality of fuel chambers in combination with fuel supply means for supplying a different fuel to each chamber, pumps one for each fuel chamber adapted to force fuel into said fuel chambers, said pumps located within the carburetor part of the actuating means of such pumps being located within the carburetor.

2. In combination with an internal combustion engine a carburetor having a mixing chamber, a plurality of fuel chambers for receiving fuels of different character, means for introducing fuel from the fuel chambers to the mixing chamber, means for conveying fuel to the fuel chambers from a supply source, including a conduit line, one for each fuel chamber, a pump in each of said fuel chambers, and an operating connection from said engine to said pump whereby said pump is driven and whereby fuel is drawn through

5 said conduit lines by said pumps into said fuel chambers, and a separate overflow chamber for each of said fuel chambers and a conduit from each of said overflow chambers back to the source of supply part of the actuating means of such pumps being located within the carburetor.

10 3. In a carburetor, a fuel holding chamber, fuel supply means and means for drawing fuel into said chamber, said means located within the carburetor, substantially all of said means for drawing fuel into the fuel chamber being located below the fuel level within said chamber and a portion of the 15 actuating means lying within the carburetor.

20 4. In combination in an internal combustion engine, a carburetor, a fuel holding chamber in said carburetor, a fuel supply means, and a pump for drawing fuel into said fuel holding chamber, said pump located within said fuel holding chamber, said pump plunger being located substantially below the level of fuel within said fuel chamber and a portion of the plunger actuating means being 25 located within and beneath the chamber.

30 5. In a carburetor, a fuel holding chamber, fuel supply means and means for drawing fuel into said fuel chamber, said means located within the carburetor, substantially all of said means for drawing fuel into the fuel chamber being located below the fuel level within said chamber, whereby a liquid seal is provided for said fuel drawing means and a portion of the plunger actuating means being 35 located within and beneath the chamber.

40 6. In a carburetor, a fuel holding chamber, fuel supply means and means for drawing fuel into said fuel chamber, said means located within the carburetor, in combination with a driving means adapted to operate said last mentioned means, and a yielding linkage within said driving means adapted to take up motion to prevent injury of the parts when stuck, a portion of the driving means 45 being located within said fuel chamber.

50 7. In combination in an internal combustion engine, a carburetor, a fuel holding chamber in said carburetor, a fuel supply means, and a pump for drawing fuel into said fuel holding chamber, said pump located within said fuel holding chamber, said pump driven by said engine, and a yielding linkage between said pump and said engine adapted to take up movement to prevent 55 breakage of parts when the same are stuck, a portion of the driving means being located within said fuel chamber.

60 8. In combination in an internal combustion engine, a carburetor, a fuel holding chamber in said carburetor, a fuel supply means, and a pump for drawing fuel into said fuel holding chamber, said pump located within said carburetor, said pump driven by

65 said engine, and a yielding linkage between said pump and said engine adapted to take up movement to prevent breakage of the parts when the same are stuck, said yielding means including a spring adapted to actuate the plunger in one direction, and an additional spring adapted to actuate the plunger actuating mechanism in the opposite direction, one of said springs being located within the fuel holding chamber.

70 9. In a carburetor, including in combination a fuel holding chamber and a fuel supplying means, said supply means including a pump which is located in said holding chamber and substantially entirely beneath the level of the fuel in it and operating means for said pump including yielding linkage a part 75 of said operating means being located within the fuel chamber and beneath the level of the fuel.

80 10. In a carburetor, a fuel holding chamber and supply means for supplying fuel to it, including a pump located in the chamber and means for driving the pump including a pair of springs, one stronger than the other, one adapted to move the pump on the compression stroke, the other adapted to move it on the suction stroke and means for periodically placing the stronger spring under compression.

85 11. In a carburetor, a fuel holding chamber and supply means for supplying fuel to it, including a pump located in the chamber and means for driving the pump including a pair of springs, one stronger than the other, one adapted to move the pump on the compression stroke, the other adapted to move it on the suction stroke and means for periodically placing the stronger spring under compression, one of said springs being located 90 within the fuel holding chamber and substantially below the level of the fuel in it.

95 100 12. In combination with an internal combustion engine a carburetor including two fuel holding chambers and a fuel supply means for supplying different fuels to each chamber said supply means including pumps for each chamber said pumps being located within it and substantially entirely beneath the level of the fuel in said chamber, and operating means for said pumps said means including a pair of springs for each pump, one of each pair being stronger than the other, said stronger spring adapted to move the pump on the compression stroke and the weaker spring adapted to move it on the suction stroke and means operated from said engine for periodically placing the stronger spring under compression.

110 115 Signed at La Porte, county of La Porte, and State of Indiana, this 27th day of March, 1924.

120 WILLIAM H. C. HIGGINS, JR.
